PRE-KNOTTED NECKTIE RACK

Salvatore J. Rock, 1809 Brickell Ave., Apt. 417,
Miami, Fla. 33129

Filed Aug. 25, 1975, Ser. No. 607,148

Term of patent 14 years

Int. Cl. D6—04

U.S. Cl. D6—118

FIG. 1 is a top plan view of a pre-knotted necktie rack showing my new design;

FIG. 2 is a front elevational view thereof;

FIG. 3 is a bottom view thereof; and

FIG. 4 is a side elevational view thereof.

I claim:

The ornamental design for a pre-knotted necktie rack, substantially as shown and described.
